Inventor:

G. W. Pennington.

UNITED STATES PATENT OFFICE.

G. W. PENNISTON, OF NORTH VERNON, INDIANA.

IMPROVEMENT IN COTTON-BALE HOOPS.

Specification forming part of Letters Patent No. 22,823, dated February 1, 1859.

To all whom it may concern:

Be it known that I, G. W. PENNISTON, of North Vernon, in the county of Jennings, in the State of Indiana, have invented a new and Improved Mode of Securing Metallic Hoops on Cotton and other Bales; and I hereby declare that the following is a full and exact description thereof, reference being had to the accompanying drawings, and to the letters of reference marked thereon.

The nature of my invention consists in the peculiar manner of constructing the iron tie or friction-key, and in its ready adjustment to the ends of the piece of hoop made use of in baling cotton or other materials, and also in the ready manner of detaching it from the bale, the same letters referring to the same parts in the different figures, in which—

Figure 1 is an iron band shown edgewise; Fig. 2, a section of the lap, showing the slots cut through the ends of the band, in which the tie or friction-key is inserted. A, Fig. 4, shows the position of the tie while the bale is in the press; Fig. 3, its position as the bale is loosed from the press. The ends of the slots B' come in contact with the sides of the tie, and the draft causes the tie to turn. At the same time the convex inner sides or shoulders of the tie 1 2, Fig. 3, come in contact with and press the ends closely together, thereby caus-

ing a friction which serves to relieve a part of the strain on the tie, and the convex bearing prevents cutting the hoop, thereby effecting two very important points—to wit, strengthening the lap and relieving the strain on the tie. Fig. 4 represents the tie as being introduced while the bale is in the press, or at the time of detaching the same, as in either case, with a common wrench or pair of pinchers, the tie, by giving it a quarter-turn, is set in its proper position for fastening or releasing the same from the bale without injury to the hoop, so that it may be used any given number of times, at pleasure.

The great advantages of this construction are that it takes less material and less expansion than any other hoop, and is much more readily applied to the bale.

Having thus fully described my invention, what I claim as my invention, and desire to secure by Letters Patent, is—

The tie A, or friction-key, constructed as described, with its convex inner bearings 1 and 2, Fig. 3, when constructed and operated in the manner and for the purposes above specified.

G. W. PENNISTON.
